[57] CLAIM

An ornamental design for a glass block, as shown.

DESCRIPTION

FIG. 1 is a front view of the glass block;
FIG. 2 is a left side view of the glass block;
FIG. 3 is a right side view of the glass block;
FIG. 4 is a top plan view of the glass block; and
FIG. 5 is a bottom plan view of the glass block;
FIG. 6 is a front cross-sectional view of the glass block
taken along lines VI—VI of FIG. 3 illustrating undulations
upon the inner surface of the glass block, giving
the glass block an undulating appearance; and,
FIG. 7 is a right side cross-sectional view of the glass
block taken along lines VII—VII of FIG. 1 illustrating
undulations upon the inner surface of the glass block,
giving the glass block an undulating appearance.
